UNITED STATES PATENT OFFICE

EARL D. MORGAN, OF LOS ANGELES, CALIFORNIA

TENT

Application filed September 5, 1925. Serial No. 54,647.

This invention has to do with tents, and is particularly concerned with that type of tent wherein the supporting structure is of a collapsible nature so it may be brought into a bundle of relatively small compass for transportation. While, of course, the tent is adapted for use in any situation where a structure of this type is desirable, it is particularly well suited to meet the requirements of automobile tourists who camp along the wayside or at beaches; this for the reason that it may be collapsed to such proportions that it may be readily packed for transport on the running board or luggage racks of vehicles.

15 The invention has for its general objects to provide a tent which may be quickly and easily erected or collapsed, one which is sufficiently sturdy and rigid, when erected, to withstand well the action of the elements, and one 20 which, when collapsed, occupies minimum storage space and is always in condition for immediate erection.

It is a more particular object of the invention to provide a tent of the character generally described above wherein all necessity for center, ridge and end poles is eliminated, the walls preferably extending vertically sufficiently to give ample head room everywhere in the tent. The total elimination of dead 30 space and supporting structure, except at the walls of the tent, gives the occupants freedom of movement, impossible in the usual structure, and allows the disposition of cots, tables, etc., to a decided advantage, as will be readily 35 understood.

Generally, I accomplish my purpose by providing a self-supporting wall structure which, in turn, supports a foldable top structure. The frame is made up of a plurality 40 of pairs of levers, the levers of each pair being pivotally connected near their centers, and the ends of the levers being pivotally connected to the ends of the levers of an adjacent pair, the general assembly being in the nature 45 of "lazy tongs," except that adjacent lever pairs are angularly disposed with respect to one another to form a three-sided frame. It will be readily seen that a structure of this kind may be collapsed or extended with a 50 minimum of effort. Furthermore, there is no

necessity for guy ropes and tent stakes to hold the frame in erected condition.

In order to reduce the longitudinal extent of the collapsed frame, I prefer to have break-joints in the levers whereby they may be folded, there being detents provided for holding them in straightened out condition when the structure is erected.

Further objects and features of the invention will be made apparent in the following 60 detailed specification, reference being had to the accompanying drawings, in which:

Fig. 1 is a perspective view showing the tent in erected condition and with the fly lowered over the open side of the tent as a 65 door;

Fig. 2 is a view similar to Fig. 1, except that the fly is shown in raised condition and supported on a folding frame work;

Fig. 2^a is a detached, contracted plan view 70 of the fly supporting framework;

Fig. 2^b is a fragmentary detail section showing the preferred method of attaching the fly supporting frame to the wall frame of the tent;

Fig. 3 is a detached, fragmentary plan view 75 of the collapsible top frame;

Fig. 4 is a section on line 4—4 of Fig. 3, except that it shows the full diagonal extent of the top frame and shows the type of connection between the top frame and the wall frame;

Fig. 5 is a section on line 5—5 of Fig. 4;

Fig. 6 is a view of the top frame in collapsed condition, the canvas covering being 85 omitted in order to expose the frame elements;

Fig. 7 is a view similar to Fig. 1, except that it shows the structure after the top has been removed;

Fig. 8 is a plan view of diagrammatic nature, but may be considered as a section taken about on line 8—8 of Fig. 9; the dotted lines showing the relative position of certain of the frame parts after the frame has been collapsed but before it has been lowered to the ground and folded;

Fig. 9 is a detached side elevation of the wall frame as viewed from the right of Fig. 7;

90

95

100

Fig. 10 is a fragmentary view of Fig. 9 looking from the direction of line 10 in that figure;

Fig. 11 is an enlarged plan detail of a typical break-joint provided in the frame levers;

Fig. 12 is a section on line 12—12 of Fig. 11;

Fig. 13 is a plan view of the frame after it has been collapsed and then lowered to the right from the position of Fig. 9; and

Fig. 14 is a side elevation of Fig. 13, but showing the frame levers in an intermediate position as they are being folded.

The canvas walls and floor of the tent are preferably sewed together into a single piece or housing of the shape clearly indicated in Fig. 7, the rear wall 10 and side walls 11 preferably having reinforcing or binding strips 12, the upper strips being provided with eyelets 13. Floor 14 may have loops 15 sewed thereto and extending horizontally therefrom to take stakes 16, though I find it ordinarily unnecessary to use such stakes, front strips 17 extend from sides 11 and are sewed at their bottom edges to floor 14, thus providing corner pockets 18 at the front of the tent as well as at the rear thereof.

The canvas walls are detachably connected to the self-supporting wall frame in the manner to be later described, and when the canvas is in detached condition it may be rolled up into a bundle of small compass or may be wrapped about the collapsed frame as a covering.

The wall frame consists of three sections, viz., back section 19 and side sections 20 and 21. In turn, each section is made up of a pair of levers 22 which are pivotally joined near their centers and pivotally connected, in effect, to the ends of the levers in the adjacent section. The pivotal connection between the lever ends is made through angle members, it following that collapse or extension of one section causes coincident collapse or extension, respectively, of the other sections, but the direction of collapse or extension of a given section is angular with respect to the direction of collapse or extension of the adjacent section. Furthermore, in order that the frame may be of less longitudinal extent when in collapsed condition, I prefer to provide break-joints in the levers, and I will describe the particular provision shown in the drawings whereby the levers may be folded, though it is to be understood that the invention, considered in its broader aspects is not limited to this particular construction, method of folding, or even to having the levers so they are foldable. Furthermore, while I have specified and shown each section as being made up of a single pair of levers, it will be understood it also lies within the scope of my broader claims to make each section up of a plurality of lever pairs.

Except for certain individual peculiarities

which I will describe later, the rear and side frame sections are identical, and therefore, I will describe but one in detail, namely, side section 21 as shown in Fig. 9. Each lever 22 includes in its make-up a channel 24, it being noted that both channels face toward the front of the tent structure when the frame is erected. Channels 24 are pivotally connected by pin 25 at a point which is approximately midway between the extreme ends of the levers, said pin extending through lugs 26. Bars 27 and 27^a, which complete the levers, are pivotally secured at 28, one to each channel, the web of the channels co-acting with the bars to limit their clockwise movement, as viewed in Fig. 9; and when the bars are at this limit of movement, they are in longitudinal alinement with the channel. The joint thus described between bar and channel will be called "break-joint a." In order to hold the rods and channels releasably in longitudinal alinement, or otherwise expressed, in unfolded condition, I provide any suitable type of detent. A preferred form of detent is illustrated in Figs. 11 and 12 of the drawings, and while these figures show the break-joint and detent of one of the rear section levers, it may be described in connection with the side frame levers since the joints and detents are identical. The illustrated and preferred form of detent is made up of a flat spring 29 secured to its associated channel by pivot pin 28 and rivet 29^a and has at its free extremity a keeper bar 30 which is adapted to lie at the end of the channel and approximately in the common plane of the flange edges of the channel when the spring is in normal position. A cam extension 31 extends upwardly from keeper 30 and is of such a shape that when lever 22 is straightened out, bar 22 coacts with cam 31 to move keeper 30 against the action of spring 29 into the dotted line positions shown in Figs. 11 and 12. Lever bar 22 is thus admitted to the channel as soon as it reaches its position of full extension, spring 29 snaps keeper 30 back to normal position and over the bar, thus releasably holding the channel and lever bar in their unfolded or extended positions.

Cam 31 also provides a grip whereby the detent may be manually grasped to release it when it is desired to fold the lever. It will be noted that the axis of pivot pin 25, which I will call the "collapsing axis" of frame section 21 is substantially parallel to the axis of pivot pins 28, which I will term the "folding axes" of the frame sections.

The upper, free end of bar 27 has a post 125 terminal 32 and an attachment button 33, the latter providing means whereby the upper, forward end of the canvas side wall may be attached to said bar. The lower end of that channel 24 which carries bar 27 is piv-

totally connected at 34 to corner angle 35; while the free end of that channel 24 which carries bar 27^a is adapted to extend into the lower end of corner pocket 18 of the canvas housing. The upper end of lever bar 27^a is pivotally connected at 36 to upper corner angle 37, this angle carrying a post extension 38 and a corner button 39, the latter providing means whereby the upper, right-hand corner of canvas side 11 may be attached thereto.

Rear section 19 is made up of levers 40 and 41 which are pivotally connected at their centers by pin 42 (Fig. 10) and are each fashioned with a break-joint *b* similar to that described in connection with the side section, except that the axes 43 of the break-joints are substantially perpendicular to the collapsing axis 42. The channel portions 44 of both rear levers open toward the front of the tent when the latter is erected; in fact, by reference to Fig. 8, it will be noted that all the channel members open to the front of the tent, and that each of them comprises the lower portion of a given lever. Detents 29, 30, serve to hold the rear section levers releasably in unfolded position. The lower end of lever 40 is pivotally connected to angle 35, the upper end of lever 41 is pivotally connected to angle 37; while the upper and lower ends of lever 40 and 41 are pivotally secured to corner angles 45 and 46, respectively, these angles being similar to angles 35 and 37, respectively, and being pivotally connected to the inner ends of the levers of the section making up the third side of the frame.

It will be noted that when the canvas walls are buttoned to the side and rear sections at their tops and are spread into the corners of the canvas, as shown in Fig. 7, the extension movement of the frame is definitely limited by the tensioned canvas, and that due to the angular disposition of the side frame sections no supporting structure is necessary to maintain the frame in erect position.

For instance, consider a single section or panel, without regard to its associated section, as a stretch of canvas held at its corners to the ends of diagonally arranged, pivotally connected levers. The upper edge of the canvas acts as a tension member to prevent collapse of the lever assembly in one direction, and the side edges of the canvas prevent collapse of said assembly in the opposite direction, it thus being evident that the section is self-supported in extended condition. The corner pockets 18 receive the lower ends of the lever so that the canvas is tensioned between them and serves to aid in holding the lever assembly extended. Then the associated panels coact with the given panel in a manner to maintain the latter erect.

Frame 47 of top T comprises arms 48, preferably of channel cross-section, which extend

radially from and are pivoted to center piece 49. The arms are releasably held in the spread condition shown in Fig. 4 by spreader arms 50 which extend from a pivotal connection with each arm into pivotal connection with spreader plate 51. Connecting the two arms 48 which extend to posts 32 of the side wall frame, is a folding bar 52 which is made up in a manner similar to the individual levers of the side frame, there being at the center of arm 52 a break-joint *c* and detent similar to joint *a* and its detent. The free ends of arms 48 have apertures 53 which are adapted to receive posts 32 and 38 when the top is placed in position on the side walls, and bar 52 not only aids as releasable means for holding the top frame in spread condition but also ties together and definitely spaces the free ends of the upwardly and forwardly extending levers of the oppositely disposed side sections. The canvas C of the top is preferably secured to center plate 49 at 54 and to the free ends of arms 48 at 55, there being a marginal strip 56 extending beyond the arms and adapted to be brought down over the upper edges of the side and rear walls and buttoned thereto at 57.

The canvas of the top is preferably extended forwardly at that side of the frame which is fitted with bar 52 to form a fly F. This fly may either be used as the door of the tent, as shown in Fig. 1 and in which case buttons 58 on front strips 17 are adapted releasably to hold the fly to the walls of the tent; or it may be supported in the manner shown in Fig. 2. In the latter event I prefer to utilize a fly supporting frame made up of arms 59 which are pivotally joined at 60 and have in them break-joints *d* and detents similar to joint *a* and its detent. One end of each rod 59 has an aperture 61 whereby the rods may be hooked over posts 32 beneath top bars 48. At 62^a on the forward ends of bars 54 are pivoted posts 62 which have in them a break-joint *e* and detent similar to joint *a* and its detent. Due to the crossing of bars 54 and their general method of support and coaction with the wall frame, there is no necessity for guy ropes or any bracing structure for the fly supporting frame.

It will be seen from the above and by reference to the drawings that when the tent is erected, there is no lost space therein, for there is no supporting structure necessary except the frame along the side walls; and this frame, in turn, is self-supporting, there being no necessity for guy ropes extending from the top of the frame to stakes in the ground. The frame will, of course, ordinarily be of such height that there is ample head room even around the walls of the tent and yet there is no structure between the walls to interfere with free passage therebetween or with the placement of camping equipment.

In striking the tent, the top is first lifted

clear of pins 32 and 38 and then folded into the position shown in Fig. 6, it being necessary, of course, to break joint *c* and pull down on plate 51 before arms 48 may be swung toward one another. The canvas of the top and the fly folds inwardly with the arms and the fullness thereof is taken up by wrapping it around the collapsed top frame. Assuming that the fly supporting frame has been in use, 10 rods 59 are then freed from posts 32, joints *d* and *e* are broken, and the rods and posts folded about their break-joints and then swung together about pivot points 60 and 62^a into a package of relatively small diameter and longitudinal extent.

The canvas side and rear walls are then disconnected from the wall frame and allowed to drop to the ground. The operator then swings levers 22 of any given section, 20 preferably the rear section, together about its collapsing axis. Due to the pivotal connections between the various levers of the sections, this action causes simultaneous collapse of all the sections and brings the various members approximately into the relative position shown in dotted lines in Fig. 8. The collapsed frame is then lowered to the right, as viewed in Figs. 8 or 9, it then being, as viewed from above, in the position of Fig. 13. 25 It will be noted that by reason of the described relative disposition of the lever channels, all these channels now open upwardly, and that since the break-joint axes of the rear section are perpendicular to the collapsing axis of that section, they are approximately parallel and in alignment with the break-joint or folding axes of the side sections. The free ends of those portions of the side frame levers which carry posts 32 are then folded, 30 after breaking their joints, upon their associated channel members, while the two lever arms connected to each upper angle 37 or 45, as the case may be, are simultaneously folded by swinging them upon their break-joint axes. The operation of folding the levers is illustrated in Fig. 14, it being understood that the folding movement is then continued until the elements are nested closely; it also being understood that Fig. 13 shows 35 the frame in a somewhat open position so the elements may be more clearly distinguished, though they may be more closely drawn together when they are prepared for packing. In this connection it may be pointed out that 40 the various levers are of such proportion and material that they may bend sufficiently to allow the illustrated overlaps without injury to the structure.

45 The folding of the levers about halves the length of the collapsed frame, giving to it such dimensions as render it easily handled and easily packed. Of course, I may provide more than one break-joint in each lever to reduce still further the length of the folded

structure, without departing from the spirit of the invention.

It is believed the outstanding advantageous features of the device will be fully understood from the foregoing, but I wish to make the reservation that the drawings and descriptions are to be considered merely as illustrative of and not restrictive on the broader claims appended hereto, for various changes in design, structure and arrangement may be made 75 without departing from the spirit and scope of the claims.

I claim:

1. In a tent, a collapsible side wall frame embodying a rear section and two side sections, each section including a pair of levers pivotally connected at their centers, angle members pivotally connecting one end of each of the levers of the side sections to an adjacent end of one of the levers of the rear section, and a break-joint in each lever; the axes of the break-joints in the levers of the side sections being substantially parallel to the axis of their pivotal connection, and the axis of the break-joints of the levers of the rear section being substantially perpendicular to the axis of their pivotal connection. 80

2. In a tent, a collapsible side wall frame embodying a plurality of pairs of levers, the levers of each pair being pivotally connected at their centers, and the ends of the levers in adjacent pairs having pivotal connection with one another whereby pivotal movement of the levers of one pair causes simultaneous pivotal movement of the other levers; and a canvas housing drawn around the frame and applied directly to the levers to limit the pivotal movement of the levers. 95

3. In a tent, a collapsible frame, a canvas housing extending about the frame, said frame embodying pairs of levers, the levers of a given pair being pivotally connected near their centers, and means for applying said housing directly to the levers to hold them 100 against pivotal movement. 110

4. In a tent, a collapsible frame embodying a plurality of collapsible side sections, a canvas housing extended about said frame when said frame is erected, one of said sections embodying a pair of levers pivotally connected near their centers, said section being put into erected and collapsed condition by selective relative pivotal movement of said levers, and said housing being applied directly to the ends of said levers when the frame is erected and thus holding said section releasably against collapse by pivotal movement of the levers in given directions. 115

120 In witness that I claim the foregoing I have hereunto subscribed my name this 21st day of August, 1925.

EARL D. MORGAN.
